OR D 12,239

Design No. 12,239, dated April 26, 1881.

UNITED STATES PATENT OFFICE.

GEORGE WILKINSON, OF PROVIDENCE, RHODE ISLAND, ASSIGNOR TO
GORHAM MANUFACTURING COMPANY, OF SAME PLACE.

DESIGN FOR A SPOON AND FORK HANDLE.

SPECIFICATION forming part of Design No. 12,239, dated April 26, 1881.

Application filed March 21, 1881. Term of patent 7 years.

To all whom it may concern:

Be it known that I, GEORGE WILKINSON, a citizen of the United States, residing at Providence, in the county of Providence and State 5 of Rhode Island, have invented and produced a new and original Design for Spoon and Fork Handles, of which the following is a specification, reference being had to the accompanying photographs, forming part thereof.

Figure 1 is a front view of the design, and Fig. 2 a reverse view, these two views being deemed necessary to fully illustrate my design.

At the point designated A is a shell-like decoration.

At the point designated B is a transverse ornamental band, in the center of which is a rosette, and on either side of the rosette is an insect.

The portion of the design designated C consists of a vine and leaves, arranged in scroll-like form above and below the transverse band, 20 tapering as it descends.

The several features of ornamentation above described are to be substantially such as shown in the accompanying photographic illustration. 25

I claim as my invention—

The design for spoon and fork handles, consisting of the parts A, B, and C, substantially as herein shown.

GEORGE WILKINSON.
